UNITED STATES PATENT OFFICE

DONALD W. PERIN, OF BROOKLINE, MASSACHUSETTS, ASSIGNOR TO AMERICAN FREIGHT SERVICE, INC., OF NEW YORK, N. Y., A CORPORATION OF DELAWARE

LATCHING MECHANISM

Application filed December 19, 1927. Serial No. 241,240.

This invention relates to an improvement in latching mechanism and more particularly in latching mechanism adapted to secure in position upon a platform a container movable into the said position from either of two opposite directions.

The broad idea of providing tracks on a platform for guiding a movable container into a desired position thereon and of providing latching mechanism for securing the container in such position is old and well known, being shown, for example, in my Patent No. 1,418,966, dated June 6, 1922. The construction there set forth however necessitates the moving of the container onto the platform in one direction only and it has been found desirable to provide a construction which will function regardless of the direction in which the container is moved over the tracks on the platform. This is of particular importance in connection with the mounting of containers transversely of a platform, as for example, the platform of a flat car in which case the container should be movable onto or removable from the platform at either side of the car.

The primary object of this invention is to provide latching mechanism which will permit a container to be loaded onto tracks on a platform in either of two directions and to be removed therefrom in either direction regardless of the direction in which it was loaded upon the platform and which will lock the container in a predetermined position on said platform. A further object of this invention is to provide latching mechanism including a hook which, as the container is moved into the desired position, will be depressed by the container but which can be retracted until the hook is free to return to its normal position, and then advanced into the locking position. Other objects will be apparent to one skilled in the art from an examination of the following description and of the drawings which form a part thereof, and in which:

Fig. 1 is a plan view of a portion of the platform of a flat car adapted to receive on tracks a plurality of containers and provided

with latching mechanism for securing such containers in position:

Fig. 2 is a side elevation of the flat car shown in Fig. 1;

Fig. 3 is an enlarged plan view of a latch in the functioning position;

Fig. 4 is a sectional view of such latch in engagement with a portion of a container taken along the line 4—4 on Fig. 3;

Fig. 5 is a view similar to Fig. 4, the parts, however, being in the partially released position;

Fig. 6 is a view similar to Figs. 4 and 5, with the latch in the entirely released position;

Fig. 7 is a view similar to Figs. 4 and 5 showing, in full lines, the hook depressed by the container and indicating, in dotted lines, the latch retracted sufficiently to release the hook;

Fig. 8 is a cross sectional view taken along the line 8—8 of Fig. 3;

Fig. 9 is a front elevation of a latch in the raised position upon a flat car;

Fig. 10 is a side elevation on a reduced scale of a portion of a container and the latches one on one side, one latch in engagement and the other latch out of contact; and

Fig. 11 is a side elevation of one detail of the latching mechanism.

This invention is illustrated in the drawings as applied to a flat car 10, the platform 11 of which is provided with a plurality of suitably spaced tracks 12 adapted to receive casters 17 on the bottom of a container 18 in a manner disclosed in my prior patent. It will be understood that the containers 18 are to be secured in position by latches 13 suitably arranged outside the track adjacent each end thereof. As shown in the drawing two pair of latches 13 are provided for each container, the pair at one edge facing the pair at the other edge. Laterally projecting from each side of the container 18 near the end thereof are pins 14 which may be, as shown in Fig. 10, carried by brackets 15 suitably secured on longitudinally extending beams 16 which form a part of the container 18.

Each latch 13 comprises a base including a base plate 20 and a block 21, a hook 22 pivot-

ally mounted in the block 21 and a handle 23 by which the latch is operated. The base plate 20 is rigidly secured upon the platform 11 in any suitable way and has a pair of longitudinally extending parallel walls 24 offset at the rear end of the plate. The walls 24 define an open pocket 25 having an enlargement 26 at the rear end of the plate. Flanges 27 on the walls 24 overhang the pocket 25 and its enlargement 26 providing guides 28, 29 at each side.

The block 21 rests on the plate 20 in the pocket 25 and has projections 30 which enter the guides 28 so that the flanges 27 prevent the block 21 from rising out of the pocket 25. In the block 21 is a central recess 31 open at the front and bottom, closed at the rear by a wall 32 and partially closed at the top by a flange 33. The side walls 34 of the recess 31 are connected at the front by a crosspiece 35 and support an axle 36.

25   Mounted in the recess 31 upon the axle 36 between the side walls 34 is the hook 22 which extends through the open front of the recess and is held in contact with the flange 33 by means of a suitable coil spring 37. The hook 22 is offset as shown in the drawings, so that the tip 38 which engages one of the pins 14 is nearer the adjacent track 12 than is the remainder of the hook. The spring 37 extends in front of the hook 22 and each end is wound around a button 38' before being secured in a block 39 both buttons and blocks being carried by the walls 34. The handle 23 is pivotally secured to the rear end of the block 21 by a pin 40 mounted in the walls 34 behind the wall 32 and extends along the pocket 25 when the latch is in the functioning position, as shown in Figs. 3, 4, 6 and 7. Intermediate its ends 40 the handle 23 is provided with a slot 41 between the walls of which is a dog 42 pivotally mounted on a pin 43 and having a nose 44.

In the enlargement 26 of the pocket 25 is mounted a slideable block 45 having flanges 46 which extend into the guides 29 formed in the walls 24. The block 45 is provided with a pair of bosses 47 and 48, one adjacent each end of the block, and a central post 49. The post 49 of the block 45 enters the slot 41 in the handle 23 when the handle is in the position shown in Fig. 4 and in its upper surface is formed a notch 50 which, under certain conditions, receives the nose 44 of the dog 42. The block 45 is adjustably secured within the enlargement 26 of the pocket 25 by means of bolts 51 which threadedly engage the bosses 47, 48 and pass freely through holes in the walls 24 which extend partly across the rear of the plate 20. Suitable nuts 61 coact with the heads 62 of the bolts 51 to fix the bolts in the walls 24 and lock them against movement. Pivotedly mounted upon a post 52 carried by the boss 47 is a bar 53 having at the center a tongue 54 which may extend over the dog 42. The boss 48 carries a flanged arm 55 below

which the bar 53 rests when in the position shown in Fig. 4. A suitably formed spring 57 carried by the arm 55 coacts with the arm to secure the bar 53 removably in the locking position. If it be desired to fix the bar in that position and prevent meddling with it a chain (not shown) carried by the platform may be passed through a hole 58 provided in one end of the bar. A bridge 60 connecting the walls 26 of the plate 20 extends over the block 21 and the handle 23 at such a height that it does not in any way interfere with the movement of the block 21 in the pocket 25.

Openings 63, 64 in the bottom of the base plate 20 and in the walls 24 are provided to permit the removal and escape of dirt, snow, ice, or other matter that might interfere with the operation of the handles 23. The openings 65 in the bottom of the plate 20 near the rear walls 24 permit the turning of the nuts 61.

The container 18 may be loaded onto the car 10 from either side being guided into the proper position on the platform 11 by the engagement of its casters 17 in the tracks 12 the hooks 22 of all the latches usually being in their normal raised position. The forward pair of pins 14 on the container as they travel over the platform strike the hooks 22 of the first pair of latches and depress them against the tension of the springs 37 as shown in full lines on Fig. 7. As soon as these pins pass beyond the hooks 22 a sufficient distance the hooks will return to the normal positions. When the forward pair of pins 14 reach the second pair of latches 13 which as shown in Fig. 10 face the first pair of latches they are engaged by the tips 38 of the latch hooks and further progress of the container is prevented.

As the forward pair of pins 14 engage the hooks 22 of the second pair of latches the rearward pair of pins strike and depress the hooks 22 of the first pair of latches (see Fig. 7). In order to secure the container upon the platform the block 21 of each of the first pair of latches is retracted by the handle into the dotted line position of Fig. 7, the bar 53 being swung from the locking position into a position in which it does not interfere with the movement of the handle. The block 21 is retracted until the tip 38 of the hook 22 is released from the engaging pin 14 and is free to return to its normal position. Then the block 21 is advanced until as shown in Fig. 5 the tip 38 engages the pin 14. The nose 44 of the dog 42 enters the notch 50 of the post 49 and the handle is swung down on the pin 40 into the position shown in Fig. 4 forcing the hook 22 into the final locking position. The dog 42 functions as one element of a toggle, the pin 43 being carried past the line between the pin 40 and notch 50. The bar 53 is then swung on its bolt 52 until it passes over the spring 57 and below the flange of the arm 55. The tongue 54 on the bar 53 prevents the dogs 42

from rising and breaking the toggle mentioned above. The second pair of latches 13 having previously been locked in position the container is rigidly secured upon the platform.

5 When the flat car has reached its destination the containers are released from the platform by a substantial reversal of the steps set forth above. The pair of latches 13 on the unloading side of the car are released from engagement with pins 14 in the following manner which is described with reference to one latch only, it being understood that the other latch of the pair is treated in 10 a similar manner. The locking bar 53 is swung out of the operative position and the handle 23 is raised (see Fig. 5) until the toggle formed by the dog 42 is broken. The upward movement of the handle 23 is continued until the nose 44 is lifted out of the notch 50. The block 21 is then retracted until the hook 22 is engaged by the bridge 60 and depressed (see Fig. 6) to bring the tip 38 of the hook below and out of the path of travel of 20 the pins 14. When the latch is so positioned the handle 23 will drop (see Fig. 6) so that the container 18 may be rolled off the platform. If other containers are to be loaded onto the car at the same station and from the 25 same side of the platform the latches may remain in the released position but customarily the latches will be restored to the normal position so that a container may be rolled into the platform from either side and its forward 30 end be secured in the desired position automatically.

While this invention has been set forth in connection with the locking of a container upon a platform, the container being guided 40 to the desired position by the engagement of casters with a track, it is not limited thereto since such latches could be employed in various embodiments, the essence of the invention residing in the fact that the latches permit 45 the free movement of the article locked thereby in either of two directions, while normally in a position to limit the movement in one of said directions and to permit the free movement in the other direction as is set forth in 50 the following claims which disclose the spirit and scope of this invention.

I claim:

1. Latching mechanism for securing in position upon a platform a container movable 55 into said position from either of two opposite directions, said mechanism including two sets of latches, so located that when the container is moved in one direction, the first set permits and the second set limits such movement 60 and, when the container is moved in the opposite direction, the first set limits and the second set permits such movement.

2. Latching mechanism for securing in position upon a platform a container movable 65 into said position from either of two opposite

directions, said mechanism including a plurality of latches, each latch having a hook, said latches being divided into two sets so located that, when the container is moved in one direction, the hooks of the first set of latches permit and the hooks of the second set of latches limit such movement, and when the container is moved in the opposite direction, the hooks of the first set of latches limit and the hooks of the second set of latches permit such movement. 70

3. Latching mechanism for securing in position upon a platform a container movable into said position from either of two opposite directions, said mechanism comprising a plurality of pins on said container and a plurality of latches, one for each pin, each of said latches being engaged by certain of said pins during the movement of said container and acting to permit movement of said container in one direction and to prevent movement of said container in the opposite direction. 80

4. Latching mechanism for securing in position upon a platform a container movable into said position from either of two opposite directions, said mechanism comprising a plurality of pins on said container, and a plurality of latches, one for each pin, each said latch including a pivoted hook which is engaged by certain of said pins during the movement of said container, and acts to permit movement of said container in one direction and to prevent movement of said container in the opposite direction. 90

5. Latching mechanism for securing in position upon a platform a container movable into said position from either of two opposite directions, said mechanism comprising a plurality of pins on said container, and a plurality of latches, one for each pin, each said latch including a base mounted upon said platform and a hook pivoted upon said base, which hook is engaged by certain of said pins during the movement of said container and acts to permit movement of said container in one direction and to prevent movement of said container in the opposite direction. 100

6. Latching mechanism for securing in position upon a platform a container movable into said position from either of two opposite directions, said mechanism comprising a plurality of pins on said container, and a plurality of latches, one for each pin, each said latch including a base mounted upon said platform, a hook pivoted upon said base, and means holding said hook normally in a raised position, which hook is engaged by certain of said pins during the movement of said container being depressed by said pins to permit movement of said container in one direction and preventing movement of said container in the opposite direction. 110

7. Latching mechanism for securing in position upon a platform a container movable 120

into said position from either of two opposite directions, said mechanism comprising a plurality of pins on said container, and a plurality of latches, one for each pin, each said latch including a base mounted upon said platform, a hook pivoted upon said base, and a spring holding said hook normally in a raised position, which hook is engaged by certain of said pins during the movement of said container, being depressed by said pins to permit movement of said container in one direction and preventing movement of said container in the opposite direction.

8. Latching mechanism for securing in position upon a platform a container movable into said position from either of two opposite directions, said mechanism comprising a plurality of pins laterally projecting from said container and a plurality of latches, one for each pin, each said latch including a base plate, a block slideable in said plate, a hook pivoted on said block, means holding said hook normally in a raised position, which hook is engaged by one of the pins during the movement of said container, being depressed by said pin to permit movement of said container in one direction and preventing movement of said container in the opposite direction and means for retracting said block and hook in said plate when said hook is depressed to withdraw said hook from below said pin.

9. Latching mechanism for securing in position upon a platform a container movable into said position from either of two opposite directions, said mechanism comprising a plurality of pins laterally projecting from said container and a plurality of latches, one for each pin, each said latch including a base plate, a block slideable in said plate, a hook pivoted on said block, means holding said hook normally in a raised position, which hook is engaged by one of said pins during the movement of said container, being depressed by said pin to permit movement of said container in one direction and preventing movement of said container in the opposite direction and means for retracting said block and hook in said plate when said hook is depressed to withdraw said hook from below said pin and then advancing said block to bring said hook into latching engagement with said pin.

10. Latching mechanism for securing in position upon a platform a container movable into said position from either of two opposite directions, said mechanism comprising a plurality of pins projecting laterally from said container and a plurality of latches, one for each pin, each latch including a hook normally in the path of one of said pins to limit the movement of said container in one of said directions and means for retracting said hook in the path of said pin and then removing the hook from said path to permit the movement of said container in said direction.

11. Latching mechanism for securing in

position upon a platform a container movable into said position from either of two opposite directions, said mechanism comprising a plurality of pins projecting laterally from said container and a plurality of latches, one for each pin, each latch including a base plate, a block slideable in said base plate, a hook pivotally mounted in said block, a spring normally holding said hook in the path of one of said pins to limit the movement of said container in one of said directions, means for sliding said block in said base plate to retract said hook in the path of said pin and means for removing said hook from the path of said pin in opposition to the tension of said spring to permit the movement of said container in said direction.

12. Latching mechanism for securing in position upon a platform a container movable into said position from either of two opposite directions, said mechanism comprising a plurality of pins projecting laterally from said container and a plurality of latches, one for each pin, each latch including a hook normally in the path of one of said pins and depressed by said pin when said container is moved in one of said directions into the desired position and means for retracting said hook to disengage it from said pin and permit it to resume its normal position and for advancing said hook into locking engagement with said pin to prevent movement of said container from said position in the other of said directions.

13. Latching mechanism for securing in position upon a platform a container movable into said position from either of two opposite directions, said mechanism comprising a plurality of pins projecting laterally from said container and a plurality of latches, one for each pin, each latch including a base plate, a block slideable in said base plate, a hook pivotally mounted in said block, a spring holding said hook normally in the path of one of said pins by which said hook is depressed when said container is moved in one of said directions into the desired position, and means for sliding said block in said base plate to retract said hook from engagement with said pin and permit said hook to resume its normal position and for advancing said block to bring said hook into locking engagement with said pin to permit movement of said container from said position in the other of said directions.

14. A latch comprising a base plate having a pocket therein, a block slideable in said pocket, a hook pivotally mounted on said block, a spring normally holding said hook in a predetermined position relative to said block, a bridge on said base plate and extending over said pocket, and means for sliding said block in said pocket to bring said hook into engagement with said bridge whereby

said hook is shifted out of its normal position.

15. A latch comprising a base plate having a pocket therein, a block slideable in said pocket, a hook pivotally mounted on said block, a spring normally holding said hook in a predetermined position relative to said block, a bridge on said base plate and extending over said pocket, and a handle pivotally secured to said block for sliding said block in said pocket to bring said hook into engagement with said bridge whereby said hook is shifted out of its normal position.

16. A latch comprising a base plate having a pocket therein, a block slideable in said pocket, a hook pivotally mounted on said block, a spring normally holding said hook in a predetermined position relative to said block, a bridge on said base plate and extending over said pocket, a handle pivotally secured to said block for sliding said block in said pocket to bring said hook into engagement with said bridge whereby said hook is shifted out of its normal position, and means carried by said base plate for securing said handle in a predetermined position.

17. A latch comprising a base plate having a pocket therein, a block slideable in said pocket, a hook pivotally mounted on said block, a spring normally holding said hook in a predetermined position relative to said block, a bridge on said base plate and extending over said pocket, a handle pivotally secured to said block for sliding said block in said pocket to bring said hook engagement with said bridge whereby said hook is shifted out of its normal position, and a second block in said pocket for securing said handle in a predetermined position.

18. A latch comprising a base plate having a pocket therein, a block slideable in said pocket, a hook pivotally mounted on said block, a spring normally holding said hook in a predetermined position relative to said block, a bridge on said base plate and extending over said pocket, a handle pivotally secured to said block for sliding said block in said pocket to bring said hook into engagement with said bridge whereby said hook is shifted out of its normal position, a second block in said pocket and means on said handle adapted to engage said block and secure said handle in a predetermined position.

19. A latch comprising a base plate having a pocket therein, a block slideable in said pocket, a hook pivotally mounted on said block, a spring normally holding said hook in a predetermined position relative to said block, a bridge on said base plate and extending over said pocket, and means carried by said base plate for securing said handle in a predetermined position, a second block adjustably slideable in said pocket and a dog

pivoted upon said handle and adapted to engage said block and secure said handle in a predetermined position.

Signed by me at Boston, Massachusetts, this 16th day of December, 1927.
